York

Application May 26, 1937, Serial No. 144,821

10 Claims. (Cl. 18—17)

This invention relates to timers for safely controlling the cycle of operation of individual vulcanizer presses for hollow tires. It particularly relates to arrangements wherein one such timer 5 controls the operation of two or more such presses.

A particular object of the present invention is to provide a controlling system with safety interlocks functioning to give a reliability of operation and assurance of safety to the operator hitherto unobtainable in this art. While others have controlled only the exhaust from the interior of the tires, we also positively block the entrance of either steam or hot water to the inlet line to the interior of the tires and simultaneously connect the same to a drain.

As regards safety of operation, it is axiomatic that a control system must be safe both when automatically and when manually operated. We 20 attain this end, not by a mere aggregation of old elements and instrumentalities, but by so modifying the arrangement and organization of our apparatus as to provide greater safety by a new combination.

25 We also use a permissive running arrangement in which the timer is manually started and runs uninterruptedly through its cycle if the pressure in the exhaust line is above a predetermined minimum at a time near the beginning of the cycle 30 after the presses are closed, so that the timer will not continue to operate unless a tire is in each press.

These and other objects of our invention will appear to those skilled in the art from the accompanying drawing and specification, in which is illustrated and described a specific embodiment 35 of our invention. It is our intention to claim all that we have disclosed that is new and useful.

The drawing shows the electrical, pneumatic 40 and hydraulic circuits and their associated operative members, including a cam for a timer governing two presses, for the preferred embodiment of our improved safety method utilizing the permissive starting arrangement in connection with two push-buttons.

The description of the equipment and its operation is in the order of the following résumé:

A. General description; and

50 B. Detailed description of the preferred illustrated embodiment of our invention.

Throughout the description, it must be remembered that there are three conditions of operation; (1) normal, (2) manual, and (3) for week-ends, or other protracted periods of plant inac-

tivity, during which the presses are closed and the molds kept heated but do not contain tires.

A. General description

Before proceeding with the detailed description for a typical cure, it is believed helpful to give the following brief general description to make clear the functioning of the various operating parts.

Fig. 1 is a diagrammatic view of the controlling system, showing the timer in front elevation. Fig. 2 is a side elevation, partially in section, of a detail of the timer viewed from the left-hand side in Fig. 1. In the figures, each "individual tire mold press" is hydraulically actuated by a piston governed by a reversing valve which is air-operated by a spring-opposed diaphragm. After both presses are closed, steam is admitted to the interior of each hollow tire on one side and steam is simultaneously exhausted to a drain from its other side by valves which are likewise air-operated by spring-opposed diaphragms. After the air is blown out, the steam is shut off and hot water under pressure of several hundred lbs. per sq. in. is circulated through the tire and returned by a 3-way exhaust valve to the circulating system instead of to a drain. The timer controls, by a single cam, the sequential operation of the air-valves for the several diaphragms. This cam positions a single controlling member that operates these air-valves to give the desired sequence of operations according to the various displacements of this member. The cam is rotated by a self-starting synchronous motor precisely geared to make exactly one revolution for one complete cycle of operation take the desired time.

With the timer shown, the attendant starts the timer by simultaneously pressing two push-buttons, causing the cam to run steadily forward so that each press closes, after which steam is admitted to the interior of the tire. The running switch of the timer is so arranged that the timer will stop unless the pressure in the exhaust has risen after a predetermined interval following the manual starting of the timer, failure to rise ordinarily being due to the absence of a tire from either press or failure of either of the molds to close. However, in the normal operation of this timer, it will run continuously throughout the cycle. While this "permissive feature" is similar in some respects to that shown in the Bast et al. Patent No. 1,959,336, we have applied the teachings thereof, which are for a pot heater containing a number of tires, in a novel manner

5

to the individual mold presses which face a different problem; that of safely operating such presses, a result which we attain with our improved system.

5 The steam cannot be introduced until after each press has been closed. If, for any reason, the timer stops, this is indicated by the running light on top of the timer. As long as the press is closed, steam and hot water may be admitted 10 to the interior of the tire, and the exhaust line is connected either to drain or to circulate. Whenever air pressure does not reach the diaphragm of the hydraulic reversing valve, it is held in its press-closing position by the dia- 15 phragm-opposing spring. Consequently, failure of the air-supply cannot cause the press to open. At the end of the cure, the timer shuts off the flow of hot water, admits steam to blow out the hot water to the exhaust, and then stops the flow 20 of steam, leaving the exhaust open. The timer then closes a 3-way block valve in the inlet line to the tire, simultaneously opening such line to the atmosphere, and, after a safe interval, operates the hydraulic reversing valve; the block 25 valve, having a weaker spring than the hydraulic reversing valve, will close at a lower air pressure, and the hydraulic reversing valve is additionally provided with a capacity-tank and a check-shunted resistance in series therewith to delay 30 the opening, but not the closing, of each press. Each press opens after a predetermined interval following the closure of both steam and hot water supply valves and the opening of the exhaust valve to drain.

35

B. Detailed description

In the drawing, a single timer 10 controls a pair of individual tire vulcanizing presses 11, each press having a movable mold 12 operable 40 by hydraulic piston 13 in its cylinder 14. The opening and closing ends of hydraulic cylinder 14 are connected with hydraulic reversing valve 15 by the opening and closing lines 16 and 17 respectively. Hydraulic pressure supply line 18 is connected to the hydraulic reversing valve as 45 is its exhaust hydraulic line 19. Hydraulic reversing valve 15 is positioned by air-operated diaphragm 20 opposed by a strong spring 21. A 3-way block valve 37 is likewise positioned by 50 air-operated diaphragm 38 of the same size as diaphragm 20 and opposed by a weaker spring 39, the arrangement being such that valve 37 will have moved to completely block the fluids entering the supply line 35 and connect the 55 same to atmosphere before reversing valve 15 is moved at all from its press-closing position. Steam supply valve 22 is likewise positioned by its air-operated diaphragm 23 opposed by spring 24, this valve being of the spring-closed type 60 as is also hot water supply valve 25 with its air-operated diaphragm 26 opposed by spring 27. Exhaust valve 28 is air-operated by its diaphragm 29 opposed by spring 30. This valve is of the 65 3-way type for selectively connecting the exhaust with drain 31 or circulating line 32, which is connected back to the inlet of hot water valve 25, the exhaust line 33 from the interior of the tires being connected therewith at 34. Inlet line 35 is connected with the interior of 70 each tire at inlet connection 36, to connect steam and hot water valves 22 and 25 through block valve 31 with the interior of the tires.

In timer 10, an electric motor 40 of the self-starting synchronous type drives changeable gears 41 and 42, and shaft 43, to which disc

cam 44 is attached normal to the axis of shaft 43. Cylinder hub 45 of the cam has braking ball 46 movable vertically in a fixed groove 47 so that the cam can turn freely only in a forward direction, i. e., clockwise in the figure. The periphery 5 of cam 44 is made up of circular portions of different radii corresponding with the desired operations. Air nozzle 48 has ball 49 attached thereto to act as a sled-runner and thus space the end of air nozzle 48 just clear of the front 10 surface of the cam so that it cannot hinder the motion thereof. Air-supply line 50 contains cock 51, normally open but shown closed by its handle 51' in the drawing. Bellows 52, connected to air-supply line 50 is fixed at its upper end, 15 the lower end being free to expand downwardly with an increase of air-pressure therein. Feed resistance 53 is located in the air-supply line just upstream of the bellows. Flexible air-line 54 connects the interior of bellows 52 with nozzle 20 48, which nozzle is attached to the lefthand end of lever 55, which is pivotally connected by pin 56 to the frame 10' of timer 10 and to the depending portion 57 of bellows 52 by pin 58 attached thereto so that the motion of the bellows 25 results in a corresponding magnified motion of nozzle 48. Roller 59 is rotatably mounted on pin 60 also attached to the lower end of depending portion 57 of bellows 52. Control lever 61 is pivotally mounted at its lefthand end on pin 30 62 which is attached to timer frame 10', the righthand end being biased upwardly by tension spring 63, the upper end of which is likewise attached to timer frame 10'. Roller 59 attached to the bottom portion of bellows 52 presses 35 against the upper edge of control lever 61 to position it according to the then effective edge of cam 44. Bumps on the lower edge of control lever 61 coactingly abut air-valves 64, 65 and 66 respectively for operating the reversing valve 40 15 for the presses, steam valve 22 and hot water valve 25. Adjustable bumper head 67, having sliding pin 68 biased downwardly by spring 69, is provided for each of the air-valves so that the 45 lower end of sliding pin 68 may abut the corresponding stem 70 of each of air-valves 64, 65 and 66. Each air-valve is connected with air-supply line 50 downstream of cock 51. Air-valve 66 is connected by line 71 to diaphragms 26 and 29 respectively of hot water valve 25 50 and exhaust valve 28, air-valve 66 being of the reverse-acting type so that line 71 is normally disconnected thereby from air-supply line 50 and, when stem 70 of air-valve 66 is depressed, the air-pressure reaches line 71 from air-supply 55 50. Line 72 connects air-valve 65 with diaphragm 23 of steam valve 22. This air-line 72 contains reverse-acting air-valves 73 which are closed except when movable molds 12 of presses 60 11 are closed, at which time these air-valves 73 connect control air-valve 65 with diaphragm 23. Line 74 connects air-valve 64 with diaphragm 20 of hydraulic reversing valve 15. This line is also connected with the diaphragm 38 of block valve 37, as before mentioned. Line 74 also contains 65 capacity tank 77 with series-resistance 78 and check valve 79 shunted around resistance 78 so that each press closes quickly and promptly, but opens slowly and in a delayed manner.

To operate electrical motor 40 of timer 10, an 70 electrical system is provided as follows: blade 80 is biased downwardly by its own elasticity so that its end portion may abut stud-cam 81 on the face of cam 44. Running blade 83 is connected to one line 82 of the current supply. Blade 80 opens 75

from running-blade 83 when stud-cam 81 raises the end of blade 80. Blade 80 is connected by wire 84 with the lower terminal 85 of coil 86 of motor 40. The running of motor 40 turns cam 44 so that its stud-cam 81" raises blade 80' to close against starting blade 87, which is connected by wire 88 containing two push-buttons 89 (giving two-hand "safety" starting), with wire 84 which is connected with lower terminal 85 of motor-coil 86, this wire 88 also contains an additional switch means and a relay holding-coil, as will be described later. The upper terminal 90 of coil 86, which is shunted through neon-light 91, is connected with wire 92 which, like 82, is connected with the current supply source.

Stud-cam 81" is so located relative to blade 80' of a separate starting switch, the fixed blade of which is blade 87, that starting-switch blades 80'-87 close shortly before running-switch blades 80-83 are separated at the end of a cycle as in Fig. 1. Stud-cam 81 is of such a length and so located relative to stud-cam 81" that stud-cam 81" will not only have closed blades 80'-87 before blades 80-83 open at the end of a cycle but will cause blades 80'-87 to separate before cam 81 brings blades 80-83 to again contact each other. Starting switch blades 80'-87 are in series with the two button starting switches 89 in line 88. Holding relay coil 114 is in series with starting switch blades 80'-87 (as are blades 75-76 opened by handle 51' of air-supply cock 51) and relay contacts 115-116 are in shunt with the two button starting switches 89, contact 115 being operated by armature 115' and its holding coil 114. From the foregoing and the figure, it is clear that the arrangement is such that a momentary simultaneous pushing of the two button switches 89 is effective to start the cycle of operation only while stud-cam 81" forces blade 80' against blade 87, in other words at the beginning of a cycle to start the same. In any event, the attendant can tell from running-light 91 whether or not the timer has started upon its cycle of operation.

Motor 40 then operates the timer until cam 81" rides out from under blade 80' to disconnect the same from blade 87. The motor then continues to run only if switch blades 95-96 and 98-99 are closed respectively by stud-cam 94 and bellows 101 which is connected with exhaust line 33 by tubing 102, which closure occurs in normal operation. If, however, the pressure in exhaust line 33 is not sufficiently high to close contacts 98-99 before blade 80 runs off of cam 81 (relatively speaking), armature 115' will drop so that motor 40 will stop. When the pressure in exhaust line 33 subsequently rises enough to cause bellows 101 to close contacts 98-99, this will not cause motor 40 to run since resistance 118 in series with coil 117 is so high that the pull of coil 117 on armature 115' is not sufficient to raise the same although adequate for holding it once it has been raised. (In other words, this is a "permissive" system of operating a timer for individual presses.) After the timer has thus stopped due to the failure of steam under pressure to reach exhaust line 33 at the proper moment, it is necessary for the attendant to manually raise armature 115' to restart the timer. Its failure to operate within the proper time indicates defective operation of some part of the mechanism so that the attendant would look for the source of trouble before manually closing the switch. Experience has shown that the cure is

ordinarily not sufficiently advanced to spoil the tire at this time.

It is evident that a momentary simultaneous push of the two button switches 89 will suffice to positively cause motor 40 to continue to run long enough to drive stud-cam 81 clear of blade 80 thus bringing cam 44 to a position where the presses close and, upon such closure, steam is supplied to the tires. Once cam 81 has moved clear of the end of blade 80 so that blade 80 contacts blade 83, this contact closes the running circuit of motor 40 and in effect disconnects the starting circuit 88, including switches 89, and the permissive circuit, including switch blades 95-96 and 98-99 until the next cycle of operation subsequent to the manual and simultaneous closing of both switches 89.

As earlier noted briefly, the handle of cock 51 is provided with insulated spur portion 51' for opening blade 75 from blade 76 of a switch in line 88 in series with the two button starting switches 89, the arrangement being such that in shutting off the air-supply from line 50 by cock 51, insulated portion 51' opens the switch so that motor 40 of the timer cannot be started as long as the air-supply is shut off.

Upper end 100 of bellows 101 is movable, its interior being connected, as earlier mentioned, by pressure pipe 102 with the exhaust line so that the presence of any inflating fluid, e. g., steam or hot water, in exhaust line 33 causes bellows end 100 to rise to a position corresponding with the then pressure of the exhaust, bellows end 100 then closes blades 98-99 to cause motor 40 to start, assuming that blades 95-96 are then closed by stud-cam 94.

We do not wish to be restricted to air-operation of the timer and its associated presses and their valve-operating means. The systems that we have taught would function equally as well with, e. g., electrical operation. Also, with electrical operation we may use a limit switch for the block valve so that the press-reversing valve cannot be opened until after the block valve is in blocking relation to the supply line and connects the interior of the hollow article with a drain. Similarly, we may choose in certain cases to rely only upon capacity tank 77, with or without its related resistance 78 and shunting check valve 79, to cause the opening of the press to be delayed for a safe interval after the block valve has been brought to a fluid-supply blocking position. We will not burden this specification further by discussing other useful modifications of the disclosures herein, such as will be evident to anyone skilled in this art.

The terms and expressions which we have employed are used as terms of description and not of limitation, and we have no intention, in the use of such terms and expressions, of excluding any equivalents of the features shown and described and portions thereof, but recognize that various modifications are possible within the scope of the invention claimed.

We claim:

1. In an apparatus including a press for heat-processing a hollow article, the combination with means for governing the closing and opening of the press, and means for controlling the supply of an inflating fluid under pressure to such hollow article and the exhausting of such fluid therefrom: of means operatively connected with said press-governing means and connected in series with said fluid-supply controlling means and constructed and arranged to positively block the

supply to the interior of the hollow article before said press opening means can act.

2. In an apparatus including a press for heat-processing a hollow article, the combination with means for governing the closing and opening of the press, means for controlling the supply of an inflating fluid under pressure to such hollow article and the exhausting of such fluid therefrom: of means operatively connected with said press-governing means and connected in series with said fluid-supply controlling means and constructed and arranged to positively block the supply to the interior of the hollow article and to connect said interior to exhaust before such press opening means can act.

3. In an apparatus including a press for heat-processing a hollow article, the combination with a control member, a plurality of pilot means operated thereby, a plurality of servomotor means respectively governed by said pilot means, means operatively associated with one of said servomotor means for controlling the opening and closing of the press, means operatively associated with one of said servomotor means for controlling the supply of an inflating fluid under pressure to such hollow article and the exhausting of said fluid therefrom, both of said controlling means being operated by its associated said servomotor means, and piping connecting said fluid controlling means with the interior of such hollow article: of means operatively connected to and governed by the pilot means for the press-controlling means and connected in said piping between said fluid-supplying means and said article and arranged to positively block the supply to the interior of the hollow article and to connect said interior to exhaust before said press-opening means can act.

4. In a cyclically operated apparatus including a press for heat-processing a hollow article, the combination with a timer, means for governing the closing and opening of the press, and means for controlling the supplying of an inflating fluid under pressure to such hollow article and the exhausting of such fluid therefrom, the sequential actuation of said means being governed by said timer: of means operatively connected with the press-governing means and connected in series with said fluid-supplying means and constructed to positively block the supply to the interior of the hollow article and to connect said interior to exhaust before said press-governing means can act.

5. In a cyclically operable apparatus including a press for heat-treating hollow articles, a timer including a time-operated cam, a control member positionable by said cam, a plurality of pilot means operated by said member, a plurality of servomotor means sequentially governed by said pilot means, means for controlling the operation of the press, means for controlling the supply of an inflating fluid under pressure to such hollow articles and the exhausting of said fluid therefrom, each of said controlling means being actuated respectively by an associated one of said servomotor means, and piping connecting said fluid controlling means with the interior of such hollow articles, means actuated by one of the servomotor means operatively connected with the pilot means governing said press, said last-named means being connected in said piping between said fluid-supplying means and said article and arranged to positively block the supply to the interior of the hollow article and to con-

nect said interior to drain before said press-opening means can act.

6. The combination set forth in claim 3, in which said servomotor means are pneumatically-operated, and the last named means include a delaying means having a resistance and a shunting check-valve therefor operatively connecting the press controlling means and the last named means so that the check-valve is effective only upon a press-opening movement of the pilot means for governing the opening and closing of the press.

7. In a timer system for one or more presses each for vulcanizing a hollow article, the combination of a timer including a cam, an electric motor for driving said cam at constant speed, and a controlling member positioned by said cam; a plurality of means controlled by said member comprising means for governing the operation of the press, means for supplying an inflating fluid under pressure to the interior of the hollow article, and means operatively connected in series with the fluid supplying means and constructed and arranged to block the fluid supply to the interior of the hollow article and to connect such interior to exhaust before the press operating means can act to cause the opening of the press; switch means, including a manually-operable starting portion and a cam-operable portion connected to said motor and adapted to cause the latter to advance said cam to a position beyond a press-closing position and a predetermined distance beyond a fluid-supplying position subsequent to said press closing position; a running switch connected to said motor and operated by said cam from a position thereof at a predetermined distance beyond said first named position to that for the end of a cycle, thus leaving a gap in the running of the timer; and means including a pressure operated switch having a pressure sensitive portion connectable to the interior of a hollow article in each press and a portion connectable by said cam to said motor and operable to cause the continued running of the latter in the gap between the first named and the last named position only if during such gap each press contains a hollow article filled with the inflating fluid under at least a predetermined pressure.

8. The combination set forth in claim 7, in which the first named means includes a pilot operated by said member and the means for supplying inflating fluid to the interior of each hollow article is servooperated by said pilot, and including an auxiliary pilot on each press connected in series with said first named pilot and operable to supply such fluid only upon the operation of said member and the closure of all of said presses, whereby said pressure operated switch continues the running of the motor-driven cam through the gap only if each press was closed and contained a hollow article filled with the inflating fluid under at least the predetermined pressure at the first named position of the cam.

9. In a timer system for a press for heat-processing a hollow article, the combination of a timer including a cam and a pilot actuated thereby, a controlling servooperable member biased toward a safe position and normally governed by said pilot, an electric motor for driving said cam at constant speed relative to said pilot, and a plurality of pilots actuated by said member, each of said pilots being normally connected to a common source of power; and a plurality of servooperable means each biased toward a safe

- position and normally governable by one of the member-actuated pilots comprising means for governing the operation of the press, means for supplying an inflating fluid under pressure to the interior of the hollow article, and means operatively connected in series with the fluid supplying means and constructed and arranged to block the fluid supply to the interior of the hollow article and to connect such interior to exhaust before the press operating means can act to cause the opening of the press; whereby, upon the interruption of the power supply, the controlling member assumes the stated safe position and thus prevents the further supply of inflating fluid until after the last named means is in its exhausting position and the press is closed.

10. The combination set forth in claim 9 including switch means, having a manually operable starting portion and a cam operable portion, connected to said motor and adapted to cause the latter to advance said cam to a position beyond a press closing position and a pre-

determined distance beyond a fluid supplying position subsequent to the attainment of said press closing position; a running switch connected to said motor and operated by said cam from a position thereof at a predetermined distance beyond said first named position to that for the end of a cycle, thus leaving a gap in the running of the timer; and means including a pressure operated switch having a pressure sensitive portion connectable to the interior of a hollow article in each press and a portion connectable by said cam to said motor and operable to cause the continued running of the latter in the gap between the first named and the last named position only if during such gap each press contains a hollow article filled with the inflating fluid under at least a predetermined pressure.
